[57] **CLAIM**

The ornamental design for an adjustable bench clamp, as shown and described.

DESCRIPTION

FIG. 1 is a perspective view of the present invention; FIG. 2 is a right side elevational view of the invention shown in FIG. 1;

FIG. 3 is a left side elevational view of the invention shown in FIG. 1;

FIG. 4 is a front elevational view of the invention shown in FIG. 1;

FIG. 5 is a back elevational view of the invention shown in FIG. 1;

FIG. 6 is a top plan view of the invention shown in FIG. 1; and,

FIG. 7 is a bottom plan view of the invention shown in FIG. 1.

FIG 2**FIG 1****FIG 3**
